UNITED STATES PATENT OFFICE.

JOHN G. PEACE, OF MICANOPY, FLORIDA.

BED-BOTTOM.

SPECIFICATION forming part of Letters Patent No. 758,276, dated April 26, 1904.

Application filed October 9, 1902. Serial No. 126,414. (No model.)

To all whom it may concern:

Be it known that I, JOHN G. PEACE, a citizen of the United States, residing at Micanopy, in the county of Alachua and State of Florida, have invented certain new and useful Improvements in Bed-Bottoms, of which the following is a full, clear, and exact description, reference being had to the accompanying drawings, forming part of this specification.

10 My invention relates to a bed-bottom having springs incorporated therein and a structure embodying lightness and adaptability to ordinary bedsteads without the requirement of the usual bed-slats for the support of the bed-bottom.

15 My invention consists in features of novelty hereinafter fully described, and pointed out in the claim.

Figure I is a top or plan view of my bed-bottom. Fig. II is a longitudinal section taken on line II II, Fig. I. Fig. III is an enlarged section taken on line III III, Fig. I. Fig. IV is an enlarged section taken on line IV IV, Fig. I, through the supporting-rod at 25 one end of the bed-bottom and showing a side view of one of the resilient wires attached to said rod. Fig. V is a view illustrating the extensibility of the resilient wire-supporting rod partially in section, taken on line V V, Fig. I. Fig. VI is a perspective view of one of the wire-holding bar-supporting brackets. Fig. VII is a perspective view of a second wire-holding bar-supporting bracket.

1 Fig. I designates the posts of the bedstead, to 35 which the end rails 2 and side rails 3 are secured.

4 Fig. I designates brackets having U-shaped sockets 5 and secured to the inside faces of the bedstead side rails 3 at either end of the bedstead, the sockets being open at the sides facing the adjacent end rail.

6 Fig. I is a bracket having upon one side a U-shaped socket 7, (see Figs. I, II, and VII,) said bracket being secured to one of the side rails 3 at the far end thereof from that occupied by a bracket 4.

8 Fig. I designates a bracket having an L-shaped socket 9 and secured to the second side rail 3 in opposition to the bracket 6. (See Figs. I and VI.) The sockets of the brackets 6 and

8 are open at their ends facing the adjacent end rail 2 of the bedstead, and they are adapted to receive a cross-bar 10, which is introduced first into the U-shaped socket of the bracket 6 and is then dropped into the L-shaped socket 55 of the bracket 8, the object of producing the sockets of different shapes being to permit the seating of the cross-bar with the brackets as close as possible to the end rail 2 and the posts in which it is mounted, and this object 60 is obtained through the described shape of the bracket-sockets that permit the introduction of the cross-bar thereinto in the manner stated.

11 Fig. I designates a cross-bar of tubular form 65 that is located at the far end of the bedstead from that occupied by the cross-bar 10 and is supported by extension-rods 12, that seat in the sockets of the brackets 4 and are movably arranged in the cross-bar 11. By the use of 70 the extension-rods 12 I am enabled to adapt the cross-bar 11 to bedsteads of different widths, the only requirement necessary to fit the bar to the bedstead being the proper withdrawal of the extension-rods to permit their 75 being seated in the sockets of the brackets 4. The cross-bar 10 is made of wood and may therefore be of sufficient length to permit its being reduced by sawing off a portion of it 80 to adapt it to the width of bedstead to which the bed-bottom is to be applied.

13 Fig. I and 13' designates wires, each connected at one end to the cross-bar 10 by bending the end 14 of the wire at an angle and inserting it through the cross-bar, as illustrated in Fig. 85 III. By inserting the angle-points 14 of the wires into holes in the cross-bar 10, in which they fit snugly, I provide a simple and efficient attachment of the wires to said cross-bar and one by which the wires are securely and firmly held to the cross-bar after being connected thereto, while at the same time they are removably connected to said bar in a manner to permit their easy attachment at any time. The wires 13 extend from the cross-bar 10 to a crossing line near the longitudinal center of the bedstead and have connected to them coil-springs 15, that occupy positions approximately midway of the length of the bedstead, the said springs being thereby 95 100 ar-

ranged in a crossing line corresponding to that over which the hips of a person lying upon the bed are positioned. The wires 13', which are interposed alternately of the wires 5 13, are of a greater length than the wires 13 and extend to a crossing line near the head of the bedstead, which is that end at which the cross-bar 11 is located. 16 designates the coil-springs, each connected at one end to the wires 10 13 and which occupy a position corresponding to that occupied by the shoulders of a person lying upon the bed.

17 designates resilient wires that are connected to the coil-springs 15, and 17' designates 15 resilient wires that are connected to the coil-springs 16. The resiliency of the wires 17 and 17' is obtained through the medium of coils 18 and 18', that are formed from the wires and wrapped around the cross-bar 11. 20 The coils are loosely wound on said cross-bar and terminate in loops, as seen at 19 in Fig. VI, that are applied to the wires to retain the coils.

20 designates tension-strips that are woven 25 alternately between the wires 13 and 13', there being two of said strips arranged in proximity to each other. One of these strips passes alternately above one wire and beneath the next succeeding wire, and so on alternately 30 across the bedstead, and the other strip passes beneath the wires that the first-named strip passes over and above the wires that the first-named strip passes under. The strips are preferably of elliptical shape in cross-section, 35 as seen in Figs. II and III, to prevent their rotation.

21 designates tension-strips woven or threaded between the wires 17 and 17' in the same manner as the strips 20 in connection with the wires 13 and 13'. By moving the tension-strips 40 toward each other the wires are drawn taut throughout the bedstead by reason of their being stretched as a result of the strips forcing them out of straight lines, due to the crossing of the wires between the strips, as illus- 45 trated in Fig. III.

I claim as my invention—

In a bed-bottom, the combination with the side rails of three approximately U-shaped brackets, two being secured to the side rails 50 near one end of the bed and one being secured near the opposite end of the bed, an approximately L-shaped bracket secured near that end of the bed that is provided with only one U-shaped bracket, a pair of cross-bars, unbroken alternate long and short wires secured rigidly at one end to one of the cross-bars, another set of alternate long and short wires, coil-springs connected at one end to the second set of alternate long and short wires, said 60 spring surrounding the other cross-bar but spaced therefrom, loops formed at the end of the coil-springs and through which the second set of alternate long and short wires pass, and a coil-spring connecting the free ends of 65 the long and short wires of the opposite cross-bars.

JOHN G. PEACE.

In presence of—
E. S. KNIGHT,
M. P. SMITH.
